UNITED STATES PATENT OFFICE.

ALBERT C. LINE, OF CHICAGO, ILLINOIS, ASSIGNOR TO WILSON-WESTERN SPORTING GOODS COMPANY, OF CHICAGO, ILLINOIS, A CORPORATION OF DELAWARE.

GOLF CLUB.

Application filed September 13, 1926. Serial No. 135,035.

The invention relates to a golf club, and particularly to the grip portion or handle thereof.

The invention is particularly adapted for use in connection with golf clubs in which a metallic tubular shaft is used. In the manufacture of a golf club employing a metallic shaft one of the difficulties has been to properly and permanently fasten to the shaft a grip that is most adaptable and the least expensive to the perfect balance of a golf club. Instead of using the old method, i. e., adhesive tape, linoleum, (linisole), felt or other under-binding material followed up by the building up of the leather grip itself, which entails a number of difficult operations and is difficult to control as to weight, the herein disclosed invention is used.

One of the principal objects of the invention is to supply a grip portion or handle of the club and to develop the bell top feature and the balance necessary to the club throughout.

It is one of the objects of the invention to employ a tapered non-metallic tube upon the metallic club shaft in the place of strips of adhesive tape, linoleum, (linisole), felt, or the like, covered, in turn, by the finished outer strip of leather.

Another of the objects of the invention is to construct a golf club embodying the metallic shaft with an inexpensive handle portion employing a non-metallic tapered tube acting as a filler, such as a tapered tube of paper, which may be cut and trimmed to size very readily, thus causing a substantial saving in time and material.

The invention will be explained and more readily understood when read in conjunction with the accompanying drawings, it being understood, however, that modifications may be made without departing from the spirit of the appended claims forming a part hereof.

In the drawings:

Figure 1 is an elevational view of a golf club employing the invention in the grip or handle portion thereof.

Figure 2 is a central longitudinal sectional view of the end of the grip portion of the club.

Figure 3 is a longitudinal sectional view of the entire grip or handle portion of the club illustrating the invention.

Figure 4 is a longitudinal sectional view of a portion of the tapered metallic shaft, and illustrating the tapered non-metallic tube thereon, and,

Figure 5 is a view similar to Figure 4, but showing a further tapering of the tapered non-metallic tube upon the tapered metallic shaft of the club.

The golf club embodying the invention is constructed with the tapered metallic shaft 65 10, to one end of which is secured the golf club head 11, of any desired character. The golf club head 11 is secured to the shaft 10 in any desired manner. The grip portion or handle generally designated 12 is secured 70 to the other end of the tapered metallic shaft 10.

In the construction of the grip portions or handles of golf clubs employing metallic shafts the practice heretofore has been to 75 surround the grip end of the metallic shaft with a strip of friction tape, linoleum, (linisole), felt, or the like, securing the strip by adhesive to the end of the shaft, and extending along the shaft the desired distance. 80 The strip mentioned is called a filler, and the strip has been covered with a finishing strip of leather, which, in turn, is secured to the filler by an adhesive. The invention herein embodies and includes a non-metallic ta- 85 pered tube 13 in place of the filler mentioned.

This non-metallic tapered tube is preferably formed of a sheet or sheets of paper, which are rolled together tightly and secured with adhesive, forming a relatively stiff tapered tubing, which, however, has considerable flexure, as required in a golf club. The normal flexure of the metallic shaft of the club is not lost because of the tapered paper tube which surrounds the grip or handle end thereof. It is very important in this case that the relative steely, torsional feel of the club remain intact. While paper rolled together in the tapered form illustrated and described is the pre- 100

ferred form of filler, I do not wish to be limited to this material, inasmuch as I may use other materials, such as papier mâché, and other compositions of material. It is, however, necessary in connection with any material which is used, that the proper taper of the tube be secured so that the tapered non-metallic tube will fit snugly against the tapered metallic shaft.

The non-metallic tapered tube 13 is fitted 110

on the tapered metallic shaft 10 by having the narrow end of the shaft 10 enter the wide end of the tube 13, whereupon the tube 13 may slide into position to the wide end 5 portion of the metallic shaft 10 until a tight fit of the tube 13 on the shaft 10 is secured. The ends of the non-metallic tapered tube 13 may then be trimmed down to the correct dimensions, preferably the large end 10 of the tube 13, being trimmed flush with the large end of the metallic shaft 10, as shown at 14 and 15. The other end of the tapered non-metallic tube 13 is cut and trimmed at the place desired, as shown at 16. The inner 15 end portion of the non-metallic tube 13 is further trimmed or shaved down, as more particularly shown at 17 in Figure 5 of the drawings. This last trim, or supplementary tapering of the tube 13, is for the purpose 20 of supplying a substantially uniform taper to the golf club shaft taken as a whole, that is, including the tapered metallic shaft and the grip or handle portion as the single shaft of the club. The tapered nonmetallic 25 tube 13 is further secured to the metallic shaft 10 by suitable adhesive.

A plug 18 is inserted into the end of the metallic tube 10, and extends into the end to any distance which may be desired. The 30 plug is tapered, so that it will fit snugly within the end of the metallic shaft 10. The plug is provided with a shoulder 19, and a taper or flared bell top design. The large ends 14 and 15 of the non-metallic tube 13, 35 and the shaft 10, respectively, abut against the shoulder 19. The outer end of the plug 18, and the finishing strip 20 may be finished in any desirable manner forming a desirable bell top shape to the grip or straight 40 taper, if desired. As shown in the drawings,

the outer end of the plug 18 is flared outwardly with the bell top design 21.

The plug 18 may be fastened securely to the tubular steel shaft 10 by means of cement, pinning or riveting, or in any other 45 suitable manner.

This structure forms a foundation of the grip proper. The final covering of leather or other material will then be wound over this structure, forming the completed grip, 50 which is securely held in position through the application of adhesive.

Having thus described my invention, what I desire to claim and secure by Letters Patent is:

1. In a golf club, a hollow tapered shaft, a paper tapered tube upon said hollow shaft, and a plug closing one end of said hollow shaft and said tapered paper tube, said plug having a shoulder near its outer end for 60 causing said closure.

2. In a golf club, a hollow tapered shaft, a non-metallic tapered tube upon said hollow shaft, and a plug closing one end of said hollow shaft and said tapered non-metallic 65 tube, said plug having a shoulder near its outer end for causing said closure, and a flared or bell-shaped outer end.

3. In a golf club, a hollow tapered shaft, a paper tapered tube upon said hollow 70 shaft, and a plug closing one end of said hollow shaft and said tapered paper tube, said plug having a shoulder near its outer end for causing said closure, and a flared or bell-shaped outer end.

In witness whereof, I hereunto subscribe my name this 9th day of September, A. D., 1926.

ALBERT C. LINK.
